UNITED STATES PATENT OFFICE.

PHELPS M. FREER, OF DETROIT, MICHIGAN.

APPARATUS FOR REMOVING WATER, GASOLINE, AND THE LIKE FROM LUBRICATING OILS.

Application filed May 7, 1924, Serial No. 711,692. Renewed April 13, 1927.

This invention relates to lubricating systems for internal combustion engines.

It is an object of the invention to provide for circulating the lubricant supply of an internal combustion engine and for removal of adulterants and foreign matter from said supply in the course of its circulation.

Another object is to circulate the lubricant supply of an internal combustion engine at a speed substantially independent of variations in the engine speed, and to release foreign matter from said lubricant during such circulation.

Another object is to provide for heating the air delivered to the carburetor of an engine and mixing with said air vaporized fuel or water removed from the lubricant supply of said engine.

These and various other objects are attained by the construction hereinafter described and illustrated in the accompanying drawings wherein:

Figure 1 is a view in side elevation of an engine, having the herein described lubricating system.

Figure 2 is a sectional elevation of a cylinder of said engine, taken on line 2-2 of Figure 1.

Figure 2^A is a modification of the structure shown in Figure 2.

Figure 3 is a sectional elevation of a lubricant-purifying device.

Figure 4 is a view in sectional elevation of an engine, and of an alternative oil circulating system associated therewith.

Figure 5 is a sectional view of the means maintaining circulation in the system shown in Figure 4.

Figures 6 and 7 are views similar to Figure 5 showing other alternative forms of purifying devices.

In these views, the reference character 1 designates an internal combustion engine of which 2 is a cylinder, 3 a piston working in said cylinder, 4 the crank-case, 5 an intake manifold and 6 the exhaust manifold.

The invention proposes to remove sediment and also gasoline, water and other foreign liquids from the lubricant supply of said engine by circulating said supply, filtering it during such circulation and subjecting it to heat derived either from the exhaust gases

or some other suitable source, to maintain circulation and vaporize foreign liquids. 55 Thus, above a portion 7 of the exhaust conduit, the invention mounts a purifying device 8. In the bottom portion of said device there is formed a boiling chamber 9, above which is an annular chamber 10, to 60 which lubricant from the crank-case is delivered by a pipe 11.

Also, there is branched into the pipe 11, a pipe 12, which communicates through a manifold 12^a with the outlets 13 of annular 65 channels 14, formed interiorly of the cylinders 2, in their lower portions.

Each of said channels, as Figure 2 shows, is so located that the lowermost piston ring 14^a lies just above said channel in the lower 70 limiting position of the piston. Thus said lower ring tends on the down-stroke to carry any excess of lubricant upon the cylinder wall into the channel 14.

In the modification shown in Figure 2^A the 75 channel 14^b in the cylinder wall is formed in part by a removable sleeve 14^c.

A disk check valve 15, located in a valve chamber 16 just above the annular chamber 10, controls ports 17 which connect the 80 chambers 10 and 16. From said valve chamber there rises centrally within the purifying device a tube 18, having on its upper end a conical spreader 19 and spaced above the latter is a deflector 20, carried by the upper portion of a wall 21.

Between said wall and the outer wall of the member 8 there is formed a chamber 22, receiving heated air through a connection 23 from a heater 24 adjacent the exhaust 90 manifold, and which delivers said air through a pipe 25 to the carburetor 26. 27 is the throttle valve controlling the flow of explosive mixture from said carburetor, and 28 is a valve controlling delivery to the carburetor of unheated air through an inlet 29. 95

To the throttle 27 is connected an actuating arm 30, to which is pivoted a rod 31, engageable through a predetermined opening movement of the throttle, with an arm 100 31^a controlling the valve 28, to open the latter and admit unheated air to the carburetor. A spring 31^b normally holds the valve 28 closed.

32 is a collecting chamber formed centrally within the separating device 8, and

33 an outlet connection from said chamber to a trap 34 which may be integral with said device. The lubricant flows into said trap at a point below the level of a filter screen 35 therein, and discharges at a point above said screen into a cooling coil 36, 37 is a discharge connection from said coil into the crank-case.

In the use of the described apparatus, the 10 exhaust heat forms globules of gas or steam in the boiling chamber 9, which globules, in rising through the tube 18 intermittently raise the liquid level therein, resulting in successive discharges from the top 15 of said tube. The disk 15 acts as a check valve permitting a free flow of lubricant into the chamber 9 but preventing pressure within said chamber from finding relief through the ports 17. The member 20 laterally deflects the lubricant discharging from the tube 18, causing it to flow down upon the spreader 19 and into the collecting chamber 32. From the latter, the lubricant flows by gravity through the trap 34 and cooling coil 36, returning finally to the crank-case. In passing through the filter screen 35 of said trap, the lubricant is freed from sediment or any solid matter which may be carried in suspension.

30 Any water, gasoline, or other liquid adulterants that may be mixed with the lubricant entering the purifying device 8 will be vaporized either by the heating of the lubricant in said device, or by spreading of the lubricant in a thin film on the spreader 20 and wall 21. The water vapor or gases thus released enter the chamber 22 and mix with the current of heated air flowing therethrough to the carburetor.

40 The described device keeps the lubricating oil free from impurities, both liquid and solid, and further effects an economy of such oil and more efficient operation by preventing any rise of the oil past the engine pistons into the combustion chambers.

50 In Figure 3, there is shown one form of a thermostatic control which may be employed to automatically regulate the degree of heat applied to the boiling chamber 9. Thus, there is secured to said chamber a strip 38 formed of two overlapped metals which are differentially expansive, when heated. Said strip is adapted at moderate engine temperatures, to bear upon the exhaust conduit, providing a path for convection travel of heat to the chamber 9. When, however, the temperature of said strip rises beyond a predetermined point, the differential expansion of its component metals withdraws the strip from contact with the exhaust pipe as Figure 3 indicates in dash lines, the convection transfer of heat being thus stopped.

60 Also in Figure 3, there is shown within the chamber 9 an electric heating element which may be energized if desired, to supple-

ment the heating effect of the exhaust conduit.

That form of the invention shown in Figures 4 and 5 circulates the lubricant, delivering it to points of use, the purification means, 70 employed in the first-described apparatus being applicable also to this modified construction but not being shown. The lubricant flows from the crank-case 40 through pipe 41 to inlet chamber 42 of boiling chamber 75 43. Heat from the exhaust pipe 44 forms a gas or vapor in the chamber 43, which rising in tube 45 effects successive discharges of the liquid therefrom. The discharged liquid is delivered through a cooling coil 46 80 to bearings 47, whence it drips back into the crank-case.

In that form of the purifying device disclosed in Figure 6, the lubricant from the crank-case enters a boiling chamber 48 through a pipe 49, there being a disk check-valve 50 within said chamber controlling the opening in the bottom thereof to which said pipe leads. 51 is a tube rising from the chamber 48 wherein the lubricant is adapted 90 to be raised by the formation of vapor or gas in the chamber 48. The lubricant is heated either by an exhaust pipe 52 arranged above and adjacent to the chamber 48 or by an electrical resistor 53 disposed in the 95 lower portion of the tube 51, or by both.

The further modification of the purifying device shown in Figure 7 differs from the construction already described only in the omission of a check-valve. 100

It is to be noted that when the described device utilizes only exhaust heat, the circulation and purification of the lubricant begins only when the engine and circulation means have been heated to a certain extent through 105 operation of said engine.

When the heating means for the circulation system is electrical or otherwise independent of the exhaust heat, the circulation may be maintained if desired, even when the 110 engine is at rest.

What I claim as my invention is:—

1. A lubricating circulation system for internal combustion engines, comprising 115 means for vaporizing liquid impurities in a portion of said system and for raising the lubricant in said portion to a higher level by means of the vaporized impurities.

2. A lubricant purifying device comprising a boiling chamber for the lubricant, a tube rising from said chamber through which the lubricant is adapted to be elevated by vapor generated in said chamber, and a spreader receiving the discharge from the upper end of said tube. 120

3. In a lubrication system, the combination with an internal combustion engine comprising a crank-case forming a lubricant reservoir, of an outlet connection leading from said reservoir, means for purifying 130

and elevating a lubricant discharging from the crank-case through said connection by the application of heat, and means for cooling said lubricant in its return to the crank case.

4. The method of purifying the lubricant supply of an engine, comprising heating the lubricant to maintain its circulation and effect vaporization of liquid impurities.

5. The method of effecting circulation of an adulterated lubricant and of removing a liquid adulterant therefrom comprising vaporization of the adulterant and elevation of the lubricant in a portion of said system under pressure of the vaporized adulterant.

6. The combination with an oil reservoir and an internal combustion engine supplied with oil from said reservoir, of means for generating gases by an application of heat to said system to maintain a delivery of oil.

7. The combination with a lubricant reservoir and an internal combustion engine supplied with lubricant from said reservoir, of means for generating gases to effect a flow of lubricant from said reservoir responsive to an application of the exhaust heat of said engine.

8. A lubricating circulation system for internal combustion engines comprising means for vaporizing liquid in a portion of said system and for raising the lubricant in

said portion to a higher level by means of said vaporization.

9. A lubricant purifying device comprising a boiling chamber for the lubricant, a tube rising through said chamber through which the lubricant is adapted to be elevated by the vapor generated in said chamber and a filter for the lubricant.

10. In a lubrication system for internal combustion engines having an exhaust manifold, a lubricant reservoir, and means dependent upon the exhaust gases passing through said manifold for maintaining the circulation of the lubricant by vaporizing the liquid adulterating the lubricant.

11. In an oil delivery system for lubrication of an internal combustion engine, a source of heat, means for maintaining a delivery of oil by an application of heat from said source to said system and thermostatically controlled means for regulating the application of said heat to said system.

12. The combination with an internal combustion engine having a lubricant reservoir and an exhaust manifold, means for utilizing the heat of the exhaust to effect a circulation of said lubricant, and means for automatically regulating the amount of heat applied from said exhaust to said system.

In testimony whereof I affix my signature.
PHELPS M. FREER.
